LAMP OR SIMILAR ARTICLE

Sidney Rubeck, New York, N. Y.

Application March 8, 1955, Serial No. 34,920

Term of patent 14 years

(Cl. D48—20)

Fig. 1

Fig. 2

Fig. 1 is a front perspective view of a lamp or similar article showing my new design.

Fig. 2 is a side perspective view thereof.

The dominant feature of my design resides in the portions shown in solid lines.

I claim:

The ornamental design for a lamp or similar article, substantially as shown and described.
